SNACK DISH OR SIMILAR ARTICLE

Noah Rubin, New York, N. Y.

Application August 19, 1953, Serial No. 26,505

Term of patent 3½ years

(Cl. D44—10)

To all whom it may concern:

Be it known that I, Noah Rubin, a citizen of the United States, residing in New York city, county, and State of New York, have invented a new, original, and ornamental Design for a Snack Dish or Similar Article, of which the following is a specification, reference being had to the accompanying drawing, forming a part thereof, in which:

Fig. 1 is a top plan view of my new design for a snack dish or similar article;

Fig. 2 is a side elevational view thereof, and Fig. 3 is a vertical cross-sectional view thereof taken along line 3—3 of Fig. 2.

I claim:

The ornamental design for snack dish or similar article, as shown.
